UNITED STATES PATENT OFFICE.

GEORGE PASHLEY AND EVAN DAVIES, OF NEW YORK, N. Y.

DESIGN FOR SUGAR-TONGS.

Specification forming part of Design No. 6,206, dated October 15, 1872.

To all whom it may concern:

Be it known that we, GEORGE PASHLEY and EVAN DAVIES, of the city, county, and State of New York, have invented a new and original Design for Sugar-Tongs, of which the following is a specification:

The drawing represents a perspective view of our new sugar-tongs.

This invention relates to a new form of sugar-tongs, which have spoon-shaped termini A A at the ends of two levers, B B, that cross each other, and are pivoted where they cross by a pin, a. The invention consists in the form of the levers B B, which are wavy, as shown, and have rings b b at their handle ends. The invention also consists in the use of the

spoon-jaws A A on sugar-tongs; and, finally, in the combination of said spoon-jaws with the levers B.

These tongs, when made of a larger size, can be used for holding ice and other articles.

We claim as our invention—

1. The levers B, shaped as shown.
2. The spoon-jaws arranged on sugar-tongs.
3. The combination of the levers B with the spoon-jaws A, as shown.

GEORGE PASHLEY.
EVAN DAVIES.
